UNITED STATES PATENT OFFICE

JAMES MEADE, OF STOUGHTON, MASSACHUSETTS, ASSIGNOR TO PLYMOUTH RUBBER COMPANY, OF STOUGHTON, MASSACHUSETTS, A CORPORATION OF MASSACHUSETTS.

MACHINE FOR TREATING ADHESIVE-COATED FABRIC.

1,137,511.

Specification of Letters Patent. Patented Apr. 27, 1915.

Application filed February 19, 1909. Serial No. 478,792.

To all whom it may concern:

Be it known that I, JAMES MEADE, a citizen of the United States, residing at Stoughton, in the county of Norfolk and 5 State of Massachusetts, have invented an Improvement in Machines for Treating Adhesive-Coated Fabric, of which the following description, in connection with the accompanying drawing, is a specification, like 10 letters on the drawing representing like parts.

This invention relates to a machine for treating an adhesive coated fabric and is particularly designed for treating that class 15 of adhesive coated fabrics in which the coating has its tacky or sticky qualities due to the presence of gutta percha or other vegetable gums or equivalent materials used in the rubber coating trade for producing an 20 adhesive coating. In this class of adhesive coated fabrics the coating is normally dry and non-adhesive, or at least sufficiently so that it may be rolled up without sticking together. The tacky or sticky condition of 25 the coating is produced by heating the coating which causes it to develop the tacky or sticky condition. The foundation fabric upon which the coating is applied varies in weight and weave according to the purpose 30 for which the coated fabric is to be used. This adhesive coated fabric has found a large use, more particularly in recent years, in the manufacture of inner-soles for shoes where a comparatively thin and cheap 35 leather base is reinforced by a layer of fabric cemented thereto. Types of such innersoles are known as the "Sleeper", and one form of which is described in the patent to Sleeper, No. 563,083, granted June 30, 40 1896, and the "Gem" described in patent to Cole No. 575,460, granted January 19, 1897. Heretofore when adhesive coated fabric has been used in the manufacture of these innersoles it has been common to wet or 45 moisten the fabric itself and to heat the coating; the moistening of the fabric being primarily for the purpose of rendering the fabric pliable or flexible so that it would more readily conform to any irregularity of 50 the surface to which it was applied, such for example as the projecting rib of an inner-sole, and the heating of the coating being primarily for the purpose of rendering it tacky or sticky. This moistening of the 55 fabric has been secured usually by passing

the entire coated fabric through a bath of hot water or live steam, while the heating of the coating has generally been performed by the subsequent application of dry heat.

One of the objects of this invention is to 60 eliminate this application of water or steam to the coated fabric for the purpose of moistening the fabric portion, because such moistening is often injurious not only to the fabric itself but also to the article to which 65 it is applied. In the manufacture of inner-soles the moistening often produces mildew spots upon the innersole, which is objectionable; again, it is often difficult properly to dry the innersoles so that as a result the 70 fabric is rotted or injured by the moisture; again, when the innersoles are properly dried so much time and space is required as to be very objectionable; again, the application of moisture to the fabric serves to remove the major or a substantial portion of the 75 sizing usually contained in such fabrics and which gives "body" to the fabric. By eliminating the application of moisture to the fabric I therefore do away with all 80 danger from mildew spots, all danger of the rotting of the fabric, enable the process of manufacture to be carried on rapidly, the innersoles to be used immediately after their completion, and further, I am enabled to use 85 a less heavy and consequently less expensive fabric and still secure the necessary degree of stiffness or body. Furthermore the leather portion of the innersole, due to 90 previous processes of manufacture, is frequently quite wet or moist when the adhesive fabric is applied thereto. In such cases the adhesive fabric will stick much more securely to the leather if the fabric be comparatively dry. Again when the fabric 95 is thoroughly moistened it becomes limp and when it is applied to the face of the inner-sole it flops down on to the "feather" edge and sticks thereto before it is fitted over the rib causing much trouble. The fabric when 100 treated by this invention rests across the top of the ribs and does not contact with the feather until it is fitted into place, nor does it stick so firmly to the rib as to pull it down out of position while being fitted in place. 105 The elimination of the application of water or steam is also of great advantage to the operator. Steam when used escapes often in large volumes from the machine and constitutes a continual nuisance while the water 110

often leaks or is thrown from the fabric on to the floor and around the machine.

One feature of the invention resides in a means for creasing the coated fabric longitudinally. This is particularly of use in connection with the manufacture of innersoles. In manufacturing such innersoles as the "Gem" above referred to the coated fabric is brought by hand into general conformation with the surface, lip, and feather of the innersole, and is then by suitable mechanical devices pressed closely into conformation, and in carrying out this operation the mechanical means acts beginning at one side of the innersole and finishing at the opposite side. This results in producing a strain upon the fabric between the two ribs, and often causes the fabric to pull away from one or the other rib. I provide means for forming one or more longitudinal creases in the coated fabric so that when it is brought roughly into conformation with the innersole there will remain, owing to the creases, a slight slackness in the fabric which will be taken up when the mechanical devices cause the coated fabric to conform closely to the ribs or lips of the innersole, and thus prevent strain on the fabric and secure a close fit. This feature of the invention is however not limited to use in a machine where the fabric is not moistened because the creasing mechanism effects the same novel and valuable function only to a less extent when the fabric is moist.

Another feature of the invention resides in means for mechanically softening the fabric which acts to break up the sizing in the fabric and to stretch the fabric and loosen up the weave thus rendering the fabric more pliable or flexible. In the particular form of the invention illustrated herein this means includes the creasing mechanism already referred to and an additional crushing roll studded with spikes. Good work can in many cases be done, however, without the use of any means for mechanically softening the fabric and the invention is not restricted to the use of such a means.

Hitherto it has been customary to make up the coated fabric into long narrow strips approximately the width of the widest innersole to be reinforced, and hence there has been considerable waste in the reinforcing of innersoles of less than the maximum width.

One feature of my invention is for the purpose of eliminating a substantial portion of this waste by providing a machine in which a plurality of strips of different widths may be used; for example, in the form shown a machine adapted for using two strips of different widths, so that the narrower innersoles may be made from a narrower fabric than the wider innersoles. This feature of the invention involves fur-

ther means for throwing the strip not used out of proximity to the heat applying means so that the coating would not be injured.

The invention will more fully appear from the accompanying description and drawings and will be particularly pointed out in the claims.

The drawings represent a preferred form of apparatus adapted for the treatment of two similar strips of coated fabric of different widths such as are used in the manufacture of innersoles for boots or shoes.

In the drawings, Figure 1 is a side elevation of the apparatus. Fig. 2 is a top plan view of the apparatus. Fig. 3 is a transverse cross-section taken on the line $x-x$, in Fig. 2. Fig. 4 is an end elevation of the mechanism at the leading-in end of the apparatus. Fig. 5 is a front elevation of the mechanism shown in Fig. 4. Fig. 6 is a view in cross-section taken on the line $y-y$ in Fig. 5.

The form of apparatus illustrated as the preferred embodiment of the invention is arranged to treat two similar strips of coated fabric of different widths.

A represents the base of the apparatus, preferably formed of wood, and adapted to rest upon a table or to be supported in any suitable way at about the level of an ordinary table or bench. On the base A is mounted the heat applying means and the means for creasing and mechanically softening the fabric. The heat applying means in the form shown comprises a flat, hollow, castiron steam-chest B, which occupies and extends over the larger part of the base. The coated fabric travels over the upper flat surface of this steam-chest, and the strips of fabric are separated by a rib C which may be formed or cast integral with the steam-chest. Steam under pressure sufficient to produce the desired temperature is admitted to, and exhausted from, the said steam-chest by means of suitable pipes, as D and E.

The steam-chest D is inclosed by a wooden casing, the side walls of which are indicated at F and G, the end walls of which above the steam-chest are open or slotted to allow the passage of the fabric therethrough, and the top of which is formed by two covers or doors H and J, hinged to the side walls G and F, respectively, and fitting against a cover strip K on top of the rib C. There is thus inclosed at each side of the rib C a space for each strip of the fabric, and this space being comparatively shallow serves to confine the heat and increase the rapidity of the softening operation upon the coating.

Each strip of fabric passes along with its uncoated side down against the upper surface of the steam-chest, and in order to prevent the overheating of the coating and its

injury or deterioration when one strip is not being used, I provide a means for lifting the strip of fabric off from the steam-chest. These means are the same for each strip 5 compartment or chamber and hence but one need be described. At suitable intervals the top of the steam-chest is grooved, as indicated at L, and the rib is cut away to form a guideway. A post M is mounted in each 10 guideway and has projecting at its base an arm N, resting in the groove L with its top surface flush with the top surface of the steam-chest. The posts M are connected together above the casing by a bar O, near the 15 center of which a handle P is provided. A pin Q in one or more of the posts limits the upward movement of the post, and a turn button R is provided which, when the bar O is elevated by means of the handle P may be 20 turned beneath the bar O to hold it and the connected posts and arms L in raised position. When, therefore, it is desired to elevate the strip of coated fabric from proximity to the heat applying means the handle 25 P is grasped and raised and the arms L lift the fabric off from the steam-chest. The turn button R is then turned beneath the bar O to maintain the fabric thus elevated. This renders unnecessary the opening of the cover 30 H, and thus retains the heat in the chamber, but if it is found necessary the door H could be opened more or less further to cool the chamber.

The mechanism for creasing and mechanically softening the fabric is placed at the leading-in end of the apparatus, or at the right-hand end, as shown in the drawings, and in the form illustrated comprises a pair of creasing rolls and a single crushing roll. 35 These rolls are duplicated for each strip, and hence it is necessary to describe but one set.

S indicates side frames bolted, as indicated at T, to the base A. In these side 40 frames the rolls are journaled. The lower creasing roll U is shown as fixed in position and provided with annular creasing grooves V. The upper creasing roll W is provided with co-operating annular creasing ribs Z, 45 and is mounted in bearing blocks A², which slide vertically in ways formed in the side frames S. Screws B² and springs C² serve to hold the upper creasing roll W adjustably and yieldingly in contact with the lower 50 creasing roll U. Preferably the creasing ribs Z are of different diameters and, as shown, the middle one is of larger diameter than those at each side, and the creasing grooves are correspondingly formed, thus 55 the central, longitudinal crease is more marked than those at the sides. The roll D² is mounted in split bearings in the side frames S, and set-screws E² are provided by means of which the split bearing may be 60 tightened up to produce more or less friction 65

on the roll D². This crushing roll is provided with a roughened periphery formed by a plurality of spikes projecting radially from the periphery thereof.

The action of the crushing and grooving 70 rolls will be apparent. The fabric is led over the crushing roll D² and between the creasing rolls U and W, and then into the heating chamber above the steam-chest. The fabric is pulled through the machine by 75 hand. As the fabric is pulled over the crushing roll the friction on the crushing roll causes the spikes F² to enter the fabric and break up the sizing contained therein and also to stretch the fabric so as to further 80 break up the sizing and separate the threads of the fabric so as to soften it mechanically and render it sufficiently pliable or flexible. This condition is further brought about by 85 the action of the creasing rolls, which preferably have a plurality, such as three, of co-operating annular ribs and grooves which act to form longitudinal creases in the fabric and consequently to break up the sizing and mechanically soften the fabric. I have 90 found the construction illustrated sufficiently softens the fabric for the purpose of making innersoles, but it is obvious that the mechanical devices could be elaborated to increase the mechanical softening of the fabric 95 if necessary.

The longitudinal creases formed by the creasing rolls give a comparatively permanent set to the fabric so that the fabric retains its creases until the mechanical devices 100 used in conforming the fabric to the ribbed surface of the innersole remove them. The fabric is laid upon the rib face of the innersole and pressed into conformation therewith in a general and preliminary way, this 105 being usually done by hand. The fabric is then pounded or pressed by machine into close conformation with the rib beginning at one edge of the innersole. As the operation proceeds and the other edge is reached 110 the cloth is not pulled away from the first edge nor does it bend the rib because the crease or creases are simply flattened out. Thus a close fit of the fabric to every portion of the rib face of the innersole is secured 115 without detrimental strain.

The reel of fabric, one only of which is illustrated at A⁹, is so arranged and the machine is so constructed that the fabric will maintain a central position laterally of the 120 machine as it is drawn therein. This is secured by extending the base forward as indicated at A¹² to present a straight lateral central edge terminating in outwardly and symmetrically beveled portions which act to 125 keep the fabric always on the straight central edge portion. The reel A⁹ may also, as illustrated, be provided with means acting to maintain it in a position midway between its supports. For this purpose coil springs 130

A¹³ of the same strength are placed on the reel spindle between each end of the reel and the supports A¹⁴.

The operation of the apparatus will be apparent. When the fabric is pulled through the apparatus the fabric portion is mechanically softened by the spiked crushing roll and the creasing rolls, longitudinal creases are formed therein, and then in passing over 10 the steam-chest the coating is by the heat rendered tacky or sticky, so that the fabric emerges at the left-hand end of the casing in condition suitable to be applied to an irregular surface, such as the ribbed surface 15 of an innersole. The method of heating employed is peculiarly advantageous because it heats the coating from the back toward the surface, thus softening the coating outwardly toward the surface and giving it its 20 maximum tacky or sticky quality immediately next to the fabric, and maintaining the surface in a "tempered" condition or condition in which it can be more readily handled. Consequently, when the fabric with its coating 25 thus conditioned is pressed into contact with the objects to which it is to be applied it will adhere readily and permanently thereto.

In using the apparatus illustrated a strip 30 of fabric of a given width suitable for wide innersoles, say 4½ inches in width, will be used in one chamber, and another strip, say 3½ inches in width, for innersoles of less width will be provided for the other chamber, and the operator will draw one or the other strip from the machine according to the width of the innersole which he is making. In case of any considerable run of one or the other strip so that one strip is required 35 to remain idle the operator will lift the handle P and swing the turn button beneath the bar O, thus elevating that strip from the surface of the steam chamber.

Having described my invention, what I 40 claim as new and desire to secure by Letters Patent, is:

1. In a machine for treating coated fabric, means for mechanically softening the fabric, and means for applying heat to the uncoated 45 side of the fabric.

2. In a machine for treating adhesive

coated fabric, means for mechanically softening the fabric including a creasing mechanism, and means for applying heat to the uncoated side of the fabric.

55

3. In a machine for treating adhesive coated fabric, means for mechanically breaking up the sizing in the fabric, means for forming a crease longitudinally of the fabric, and means for softening and rendering 60 tacky the coating without the application of moisture.

4. In a machine for treating adhesive coated fabric, means for mechanically softening the fabric, and means for softening 65 and rendering tacky the coating without the application of moisture.

5. In a machine for treating adhesive coated fabric, means for mechanically softening the fabric, a steam-chest inclosed to 70 form a chamber through which the fabric may be passed with the uncoated side in contact with the steam-chest, whereby the fabric will be rendered pliable without the application of moisture and the coating will be 75 rendered tacky by the heat.

6. In a machine for treating adhesive coated fabric, means for mechanically softening the fabric comprising a crushing roll provided with a roughened face and a pair 80 of rolls provided respectively with annular ribs and coöperating annular grooves acting to form longitudinal creases in the fabric.

7. In a machine for treating adhesive 85 coated fabric, means for forming a longitudinal crease in the fabric, and means for applying heat to the uncoated side of the fabric to soften and render tacky the coating.

90

8. In a machine for treating adhesive coated fabric, means for forming a longitudinal crease in the fabric, and means for softening and rendering tacky the coating.

In testimony whereof, I have signed my 95 name to this specification, in the presence of two subscribing witnesses.

JAMES MEADE.
